UNITED STATES PATENT OFFICE.

D. R. FRASER, OF CHICAGO, ILLINOIS, ASSIGNOR TO HIMSELF, P. W. GATES, AND THOMAS CHALMERS, OF SAME PLACE.

IMPROVEMENT IN VALVES FOR STEAM-ENGINES.

Specification forming part of Letters Patent No. 34,997, dated April 15, 1862.

To all whom it may concern:

Be it known that I, D. R. FRASER, of Chicago, in the county of Cook and State of Illinois, have invented a new and useful Improvement in Anti-Friction Slide-Valves; and I do hereby declare that the following is a full, clear, and exact description of the same, reference being had to the accompanying drawings, forming part of this specification, in which—

Figure 1 is a vertical longitudinal section of a slide-valve with my improvements applied to it. Fig. 2 is a vertical transverse section of the same. Fig. 3 is a horizontal section in the line $\alpha\alpha$ of Figs. 1 and 2. Figs. 4, 5, and 6 are modifications of valve attachments suspended according to one part of my invention.

Similar letters of reference in the several figures indicate corresponding parts.

The nature of my invention consists in a pendulous balance block or plate, in combination with a gravitating ring or rectangular frame and the platform of a slide-valve, whereby an improved arrangement of anti-friction slide-valve is obtained; second, in the use of a vertical hanger with spherical seat on its lower end for suspending the balancing mechanism of the valve; third, in the combination of vertical pins with spherical termini and the balancing mechanism of the valve; fourth, in the combination of springs and the balancing mechanism of the valve; fifth, in the combination of a slotted wedge, inclined projection of the valve-connecting rod, and retaining-nuts.

To enable others skilled in the art to make and use my invention, I will proceed to describe the same with reference to the drawings.

A is the face or valve-seat of the engine-cylinder; B, an ordinary slide-valve with a platform C added on the back of the same; D D, a rectangular frame resting on the platform. This frame is ground on its bottom and on its inner sides; so, also, is the platform C on its upper surface. The frame D D is open at top and bottom, so as to present but a narrow wearing-surface to the platform and to admit a balance-block within it.

E is a rectangular balance-block with a vertical flange on its under side, said flange be-

ing ground on its outer surface, so as to fit steam-tight against the sides of the frame D D. This block extends down into the frame a suitable distance to maintain a connection therewith, and is suspended in this position by means of a vertical bolt F, with a ball joint or seat F' on its lower end, said bolt extending down from the top of the steam-chest G and the ball fitting loosely, but steam-tight in a spherical socket H, formed in the under side of the balance-block, as shown.

Between stops $a a$ of the balance-block and the rectangular frame D D, at each end, a spring H' is arranged so as to control any up movement of the frame and hold said frame with a yielding force down upon the platform of the valve; and to control the pendulous motion of the frame in a direction at right angles to the throw of the valve two vertical pins I, with spherical ends, are extended down from the top of valve-chest and fitted loosely by means of said ends to elongated curved sockets $b b$ in the back of the balance-block, as shown.

In order to take up the slack or lost motion, a wedge J, with an oblong slot through it, is arranged against an incline projection K at the rear end of the valve, and the connecting-arm M of the valve passes through it far enough to receive on its end retaining-nuts c c, similar nuts d being provided on the arm at the front end of the valve. By slackening the nuts and lowering the wedge it is obvious that the slack will be taken up.

In Fig. 4 the balance-block E is in form of a flanged circular disk, and is supported by the bolt with spherical end within a chamber of the steam-chest cover, as shown, and the frame D D, instead of being rectangular at the points where the connection between it and the balance-block is effected, is made with a raised circular flange d', said flange extending up within the circular flange e of the disk E, as shown; or the flange e may extend down within the flange d'. In either case the flanges must be ground so as to form a steam-tight joint between themselves.

In Fig. 5 the balance-block is fitted in a chamber formed in the under side of the steam-chest cover, and held in position by a spring f on the bolt with spherical end, the

spring being interposed between a solid shoulder of the rectangular frame D D, which in this case is closed in at top, as shown.

In Fig. 6 substantially the same plan as Fig. 5, with the addition of packing-rings g between the balance-block and circumference of the chamber in the cover of the steam-chest, is shown.

The operation of the arrangement shown in Figs. 1, 2, and 3 is as follows: The block E being supported by the steam-chest cover and surrounded, steam-tight, by the frame D D, and the valve-back closed in by said frame and block from the pressure of the steam, the valve works nearly on a balance, the pressure of the steam above the inclosed part of the platform of the valve being borne by the balance-block instead of by the valve. The block is free to move to accommodate the valve in all directions upon the spherical seat of the bolt, but is kept in proper position by means of the springs and pins with spherical heads, and while so moving the rectangular packing-frame automatically adjusts itself upon the valve and around the balance-block in such manner that the joints are kept steam-tight, or as nearly so as practicable. The springs of course press down upon this frame D; but the frame does not depend upon them for its position, as its own gravity insures a proper adjustment. This I believe is a new feature in a balance-valve mechanism.

The operation of plan Fig. 4 is substantially the same as that of the plan just referred to, excepting that no controlling-pins and springs are used.

The operation of plans Figs. 5 and 6 is the same as that of the other plans, so far as the universal movement of the rectangular frame

is concerned. The principle of balancing is different, the steam in these instances acting against the balance-block with an upward pressure and upon the top of the frame with a downward pressure, and as the balance-block E is of less area than the frame D the superior pressure is upon the frame; but at the same time the relief offered to the valve by the balance-block causes it to work almost on a balance. These plans are not so good as the others.

What I claim as my invention, and desire to secure by Letters Patent, is—

1. The combination and arrangement of the suspended and universally-moving balance-block E, gravitating frame or packing D D, and platform C of slide-valve, substantially in the manner and for the purposes described.

2. The vertical bolt F, with spherical seat on its lower end for suspending the balancing mechanism of the valve, substantially in the manner and for the purpose described.

3. The combination of the vertical pins I, with spherical ends, and the bolt F F' and balancing mechanism, substantially in the manner described.

4. The combination of the springs, bolt F F', pins I, and balancing mechanism, substantially in the manner and for the purpose described.

5. The combination of the slotted wedge J, inclined projection K, connecting-arm M, retaining-nuts c c, and valve B, substantially in the manner and for the purpose described.

D. R. FRASER.
